INDICATOR FOR SUCTION CLEANERS

Harry B. White, Canton, Ohio, assignor to The
Hoover Company, North Canton, Ohio, a cor-
poration of Ohio

Application September 28, 1936, Serial No. 102,897

8 Claims. (Cl. 116—65)

This invention relates to improvements in suction cleaners and more particularly to devices adapted to be incorporated in suction cleaners for the purpose of providing a visual indication of the performance of the cleaner, and especially a warning of an increasing pressure within the dirt bag or receptacle due to an excess accumulation of dirt therein and the need for the immediate emptying thereof.

The object of the present invention is to provide an improved construction for a pressure indicator of the type which displays a readily visible signal to inform the operator when the bag should be emptied. It should be stated in this connection that indicators for the purpose mentioned have been heretofore known in the art and hence the present disclosure is concerned more especially with certain novel features of structure and design of the device and calculated to materially improve its performance and continuous dependability.

A preferred embodiment of the invention is disclosed in the accompanying drawing, in which: Figure 1 is a general view in side elevation of a suction cleaner showing the application of the improved bag pressure indicator thereto.

Figure 2 is a top plan view of the rear portion of the suction cleaner shown in Figure 1, with a portion of its top wall broken away to show the mounting of the bag pressure indicator.

Figure 3 is an enlarged view in front elevation of the bag pressure indicator removed from the cleaner and

Figure 4 is a view in vertical section taken on line 4—4 of Figure 3.

Referring to Figures 1 and 2, the cleaner to which the invention is especially adapted, consists of a main body or casing 1 having a transversely extending nozzle portion 2 at its forward end and supporting at its central portion a dome-like cover 3 which houses a motor 4 having direct driving connection with a fan located in a fan chamber immediately below the motor casing and communicating with an exhaust outlet having a large rearwardly opening flanged connection 5. A dust bag 6 is removably attached to the outlet connection through the medium of a metal ring 7 having notched ears 1a, 1a engaging a pair of bolts 8, 8 mounted at opposite sides of the flanged connection 5.

The cleaner is mounted upon wheels 9 located forwardly and rearwardly of the casing 1, and is maneuvered through the medium of a handle not shown herein, except for a portion of the bail 10 forming the lower end of the handle, and having pivotal connection with the casing 1.

Referring to the pressure indicator, the same is located adjacent the rear end of the casing 1 and is supported upon the top wall 1a of said casing between the motor 4 and the outlet con-

nection 5, and enclosed by the rear portion of the cover 3. In its general aspects, the indicator has the form of a stationary housing or chamber communicating with the entrance to the dirt bag and formed in part by an expandable bellows member which in turn is connected with a pivoted member carrying the visual indicating or signal member, said pivoted member being movable in one direction by the increasing pressure within the chamber and in the opposite direction by a spring pressure.

As shown in the drawing, the housing forming the stationary portion or frame of the indicator consists of a vertically disposed channel-shaped bracket 11, preferably a sheet metal stamping, 15 consisting of a vertical central web 11a and top and bottom transverse end webs 11b and 11c, respectively. These transverse webs 11b and 11c of the bracket extend toward the forward end of the cleaner as shown in Figure 1, the lowermost web 11c forming the base for the indicator assembly, the same being suitably anchored to the top wall 1a of the cleaner casing 1 as by screws 12 passing through one or more ears 13 stamped from the bottom web 11c of the bracket 25 11.

Firmly held by the bracket 11 and within the space included by the transverse webs 11b and 11c thereof, is a cylindrical cup-like member 14 also stamped of sheet metal and preferably having a portion of slightly reduced diameter immediately adjacent its closed or bottom end, said section of reduced diameter abutting flatwise against the vertical web 11a of the supporting bracket 11, and its open end facing forwardly, as clearly 35 shown in Figures 1 and 4. The depth of the cup member 14 is substantially the same as the transverse dimension of its supporting bracket 11, so that its open end is substantially flush with the adjacent edges of the bracket webs 11b and 11c, 40 although as clearly shown in Figure 4, the upper web 11b extends slightly beyond the edge of the cup member 14 and is provided along its side edges with a pair of upturned ears 15, 15 which likewise project forwardly a short distance beyond the open side of the cup member 14. Extending horizontally between the overhanging ends of the ears 15 at the top of the bracket 11 is a pin 45 16 with its ends passing through holes punched in the tips of said ears 15. This pin supports a 50 hinged or swinging plate 17 having a pair of lugs 17a, 17a, formed at the extremities of its top edge and bent at right angles to form ears through which the pin 16 passes. As clearly shown in Figure 4, the upper edge portion of the plate 17 55 is spaced outwardly from the open end of the cup member 14 but immediately below the hinged mounting the plate is inclined inwardly at an abrupt angle, so that its major portion normally lies in a vertical plane and substantially flush 60

with the open end of said cup member 14. Now, integral with the hinged plate 17, and located at one of its lower corners is a signal arm 18, extending a short distance below the base of the supporting bracket 11, and thence bent outwardly at substantially right angles, terminates in a rounded end bearing an upwardly facing target 18a of a bright color, such as red, at its center.

Housed within the metallic cup member 14, is an expansible bellows member 19 of comparatively thick flexible material such as rubber or rubber impregnated fabric having a general cylindrical form and consisting of two or more pleats folded to a radial depth of substantially $\frac{1}{3}$ of its diameter. The bellows member has the cup-like conformation of the metal cup member 14, having an open end of relatively large diameter and which, in the assembled indicator seats around the reduced inner end of the cup member 14, being provided with a relatively thick flange 19a surrounding its open end which seats securely against the internal shoulder 14a of the cup member 14, as clearly shown in Figure 4. At the opposite or outer end of the bellows member, there is formed a button-like knob 19b, projecting through a circular opening 17b at the center of the hinged plate 17, said opening being of a diameter substantially equal to the reduced neck portion of the button 19b, so that by forcing the latter therethrough it is securely attached to the plate. Obviously, the bellows member being made of rubber or like elastic material yields readily to the assembly operation and likewise expands and contracts axially in response to variations in pressure exerted internally or externally thereon.

Being thus sealed within the retaining cup member 14, the bellows member forms a yieldable wall of a pressure chamber which communicates with the exhaust or pressure side of the cleaner 40 through a short tube 20, having one end fitting over a short nipple 21 anchored in the vertical web 11a of the indicator supporting bracket 11 and the contacting end wall of the cup member 14, and its outer end fitted into a bore 22 cored 45 in the rear wall of the exhaust outlet connections from the cleaner casing 1. In this manner, the connection is made between the pressure chamber within the indicator and the entrance to the dirt bag 6, with the result that any change in air pressure within the bag is transmitted to the pressure chamber of the indicator. In short, the pressure within the indicator pressure chamber is always the same as that within the bag 6. Thus it follows that, as the pressure within the indicator chamber is increased beyond a predetermined minimum, the bellows member 19 will expand and this expansion transmitted to the hinged plate 17, causes the same to swing forwardly toward the dotted line position shown in 50 Figure 1 with its signal arm 18 in a horizontal position.

But in exerting its pressure against the hinged plate 17, the bellows member or better, the pressure which tends to expand the bellows member, 65 encounters an opposing pressure exerted on the plate by a coiled spring 23 which is carried on the bearing pin 16. This coil spring is made up of a considerable number of turns of light wire and while it is coiled around the bearing pin 16 has a 70 diameter large enough to permit it to slide freely along said pin. The endmost coils of the spring 23 terminate in straight end portions one of which bears against the horizontal web 11b of the supporting bracket 11 just below the spring, whereas 75 the opposite end of the spring is adapted to en-

gage one of a series of tooth-like notches 17c cut in the inclined edge of a wide V-shaped notch formed in the upper edge portion of the hinged plate 17. The obvious purpose of this spring and notch arrangement is to provide a convenient method of regulating the force exerted by the spring upon the hinged plate 17. Thus, by shifting the plate engaging end of the spring from one notch 17c to another, a slight increase or decrease in tension of the spring is obtained and this is sufficient to appreciably vary the action of the indicators so that each can be calibrated to the particular cleaner on which it is installed and thus insure uniform and accurate response to bag pressure conditions.

As heretofore stated, the indicator is mounted upon the top wall of the cleaner casing 1, and is concealed beneath the rear portion of the motor cover 3. However, its exact location, as shown in Figure 2, is one offset to one side of the body of the cleaner and just inside of the line of contact between the bottom edge of the cover 3 and the top wall of the casing 1.

Beneath the top wall 1a of the casing 1, and extending transversely of the casing with a portion lying outside of and a portion inside of the cover 3, is a chamber 24 formed by a short depending wall segment 24a integral with the top wall 1a of the casing, and a bottom closure plate 24b. This chamber is comparatively shallow, and only large enough to accommodate the lower and horizontally extended end portion of the signal arm 18. As shown in Figure 2, a slot 25 formed in the top wall 1a, and elongated in a direction lengthwise of the casing, is located just inside the adjacent bearing edge of the cover 3, and through this slot the signal arm is extended.

Located outwardly from the slot 25, and beyond the bearing edge of the cover 3 is a circular opening or window 26 preferably having a transparent closure so as to prevent the entrance of dust and dirt therethrough. This window is so located that when the bellows member is fully expanded, as shown in dotted lines Figures 1 and 4, the target 18a is positioned immediately below the window 26, and thus visible from above by the operator.

Thus, with the tension spring 23 adjusted to a predetermined minimum air pressure within the dirt bag, it is apparent that when a point is reached at which the increased air pressure in the bag overcomes the opposing spring pressure, the bellows member 19 will expand and when the pressure reaches a predetermined maximum, the expansion of the bellows member brings the signal target 18a beneath the window 26 as a warning to the operator to empty the contents of the bag.

Apart from the spring adjusting feature which permits the indicator to be properly regulated, there are other desirable and advantageous structural features to be mentioned and which contribute to its dependable performance. Due to the fact that the bellows chamber of the indicator has direct communication with the interior of the dust bag, it follows that dirt will find its way into the pressure chamber and hence provision is made for the detachable mounting of the bellows member in the cup member 14 and 65 from the hinged plate 17 so that it may be easily removed for cleaning purposes, this being ordinarily attended to by a service man and at regular intervals.

These features, among others, contributing to 75

the compact and workmanlike design of the indicator, are set forth in the appended claims in which I claim:

1. In a pressure indicator, the combination of a supporting member having a recessed portion communicating with the space under pressure, an axially expansible bellows member having an open end seating in said recessed portion to form a chamber sealed from the atmosphere, a signal member pivotally mounted on said supporting member and including a plate forming an abutment for said bellows member, the latter having a knob projecting from its plate abutting end and said plate having an opening to receive said knob, a spring acting on said plate adjacent its pivotal axis to oppose the expansion of said bellows member, and means for adjusting said spring to vary the tension exerted thereby.
2. In a bag pressure indicator for suction cleaners, the combination of a rigid cup-shaped member adapted to be mounted on the casing of a cleaner, a bellows member of annular form seating within said cupped member to form a pressure chamber communicating with the pressure side of the fan of the cleaner, a signal member hinged to swing relative to said cup-shaped member comprising a hinged plate extending over the open end thereof and having an aperture therein, said bellows member bearing at its outer end against said plate and having a button-like enlargement adapted to be inserted through said aperture, a spring acting on said signal member to oppose its movement under the expansion of said bellows, said signal member having a colored target movable into and out of signalling position with the expansion and contraction of said bellows member, said suction cleaner casing having a chamber beneath an upwardly facing wall thereof in which said target is movable and a window in said chamber through which said target is visible in its signalling position.
3. In a bag pressure indicator for a suction cleaner, the combination of a supporting frame including a cup-shaped recess, an axially extensible bellows member fitting within said recess with its interior space communicating with the pressure side of the fan of said suction cleaner, a plate having hinged connection with said supporting member and extending over the opening to said recess and having detachable aperture and button connection with the adjacent end of said bellows member, a spring acting on said plate to oppose its movement under the expansion of said bellows, and a signal arm carried by said plate and movable therewith into and out of signalling position.
4. In a pressure indicator for suction cleaners, the combination of a supporting frame having a cup-shaped recess, an axially expansible bellows member seating within said recess and forming therewith a pressure chamber communicating with the space under pressure, a plate having hinged connection with said frame and extending over said recess to provide an abutment for the free end of said bellows member, the latter having detachable connection with said plate, a spring acting on said plate at its point of hinged connection with said frame and acting to oppose its movement under the expansion of said bellows member, and a signal arm forming an integral extension of said plate.
5. In a bag pressure indicator for suction cleaners, the combination of a supporting frame including a cup-shaped member, an axially expansible bellows member substantially enclosed within said cup-shaped member and forming therewith a pressure chamber communicating with the space subject to varying pressure conditions, a spring-actuated plate hinged to said frame along one edge and extending over said cup-shaped member and having detachable connection with the free end of said bellows member, and a signal arm forming an extension of said plate remote from its hinged mounting.
6. In a pressure indicator for suction cleaners, the combination of a supporting frame having a cup-shaped recess, an axially expansible bellows member having an open end seating around the bottom of said recess and forming therewith a chamber communicating with a space subject to varying pressure conditions, a plate having hinged connection along one edge with said frame member and extending over the open end of said recess to form an abutment for the free end of said bellows member, the latter having a detachable fastening with the central portion of said plate, a spring acting on said plate to oppose its movement by said bellows member, means for adjusting the tension exerted by said spring on said plate, and a signal arm integral with said plate and projecting from an edge thereof remote from its hinged connection.
7. In a bag pressure indicator for suction cleaners, the combination of a frame having a recessed portion, an axially expansible bellows member mounted within said recessed portion and forming therewith a chamber subject to variations in air pressure in the dirt bag of said cleaners, a signal member comprising a plate having hinged connection with said frame and adapted to form an abutment for the free end of said bellows member, said hinged connection including a hinge pin, said plate having a series of stepped notches cut in the edge thereof adjacent to and extending parallel with said hinge pin, and a spiral coiled spring loosely mounted on said pin with one end adapted to bear against said frame and the other to engage one of said stepped notches.
8. In a bag pressure indicator for suction cleaners, the combination of a supporting frame, an axially extensible bellows member mounted on said frame and responsive to variations in pressure within the dirt bag of said cleaner, a signal member comprising a plate having hinged connection with said frame, the latter supporting a hinge pin engaged by ears spaced apart along one edge of said plate, the latter having a series of notches of uniformly increasing depth formed in the edge thereof adjacent said pin, and a spiral coiled spring loosely surrounding said pin between said ears and adapted to have one end bear against said frame and the other to engage one of said notches, said spring being adjustable lengthwise on said pin to permit the notch engaging end thereof to be shifted from one notch to another to vary the tension exerted by said spring.

HARRY B. WHITE.
